LUMINAIRE

Robert T. Burns, Rocky River, and Alfred K. Goetz,
Cleveland, Ohio, assignors to Westinghouse Electric
Corporation

Filed Apr. 20, 1972, Ser. No. 246,097

Term of patent 14 years

Int. Cl. D26—03

U.S. Cl. D48—31

FIG. 1

FIG. 2

FIG. 3

FIG. 4

FIG. 5

FIG. 6

FIG. 7

FIG. 8

FIG. 9

FIG. 10

FIG. 1 is a perspective view of a luminaire showing our new design;

FIG. 2 is a top plan view thereof;

FIG. 3 is a front elevational view thereof;

FIG. 4 is a side elevational view thereof;

FIG. 5 is a bottom plan view thereof;

FIG. 6 is a perspective view of a second embodiment of our new design;

FIG. 7 is a top plan view thereof;

FIG. 8 is a front elevational view thereof;

FIG. 9 is a side elevational view thereof, and

FIG. 10 is a bottom plan view thereof.

The support is shown in broken lines in FIGS. 1 and 6 for illustrative purposes only and forms no part of this invention.

We claim:

The ornamental design for a luminaire, substantially as shown and described.
